TELEVISION RECEIVER CABINET AND
CATHODE-RAY TUBE MOUNTING

Vernon A. Kamin, Elgin, and Lawrence J. Mattingly and Raymond R. Wingert, Chicago, Ill., assignors to Motorola, Inc., Chicago, Ill., a corporation of Illinois

Application January 10, 1948, Serial No. 1,593

9 Claims. (Cl. 178—5.8)

1

This invention relates generally to television receivers and more particularly to an improved cabinet and cathode ray tube mounting for a television receiver.

In the design of television receivers it is necessary to provide a cabinet which is arranged so that the screen of the cathode ray tube can be viewed and which also includes arrangement for mounting a loud speaker so that the sound thereof can be heard. For most satisfactory results the loud speaker should be mounted very close to the screen of the tube and should be arranged so that sound is directed toward the persons who are viewing the screen. The cabinet, of course, must also house an electronic chassis upon which the circuit components of the television receiver are mounted and it is desirable that the chassis be removable from the cabinet, as necessary for servicing, completely independently of the cathode ray tube and loud speaker. As the cathode ray tube is relatively long, and a relatively large chassis is required, cabinets provided for television receivers have been relatively large.

There are several problems involved in providing a satisfactory mounting for the cathode ray tube in a television receiver cabinet. In order to meet underwriters' requirements, suitable protecting means must be provided so that in the event the tube should break, the particles of glass from the tube would not be free to fly through the air and injure a person in the vicinity. As a very high vacuum exists in such tubes, breakage of the tubes might result in particles of glass being thrown with great force causing serious injury. To eliminate this danger, a transparent protecting plate is required in front of the screen or face of the cathode ray tube. This presents a problem as dust or other foreign materials accumulate between the face of the tube and the transparent protecting plate, and it is necessary to remove either the tube or the plate so that the surfaces thereof can be cleaned and the foreign matter thereby removed. It is also desirable to provide a resilient mounting for the tube so that the television receiver can be moved or shipped without removing the tube from the cabinet. This would, of course, eliminate special packing for the tube which would be required if the tube is shipped separate from the receiver.

It is, therefore, an object of the present invention to provide an improved cabinet for a television receiver.

A further object of this invention is to provide a television receiver cabinet including a resilient

2

mounting for the cathode ray tube of the receiver.

Another object of this invention is to provide improved means for protecting the cathode ray tube of a television receiver and means for sealing the space between the tube and the protecting means to prevent entry of foreign material therein.

A still further object of this invention is to provide a protecting plate for the face of a television receiver which also functions as a lens to improve the picture produced by the tube.

A feature of this invention is the provision of a television receiver cabinet having a one-piece front plate thereon including apertures for the admission of sound from the speaker of the receiver and a curved window which protects the face of the cathode ray tube of the receiver and improves the picture appearing thereon.

20 A further feature of this invention is the provision of a television receiver including a resilient gasket between the face of the cathode ray tube and the protecting plate therefor which forms a resilient mounting for the tube and prevents entry of foreign material between the face of the tube and the protecting plate.

25 Another feature of this invention is the provision of a television receiver in which the cathode ray tube and loud speaker are mounted on the receiver cabinet and the chassis for the receiver is removably supported in the cabinet independently of the tube and speaker.

30 A still further feature of this invention is the provision of a television receiver including a rectangular cabinet having a height not substantially greater than the diameter of the cathode ray tube, a width not substantially greater than the sum of the diameters of the cathode ray tube and the loud speaker, and a depth not substantially greater than the length of the cathode ray tube.

35 Further objects, features and advantages will be apparent from a consideration of the following description taken in connection with the accompanying drawings in which:

40 Fig. 1 is a front view of the receiver cabinet in accordance with the invention;

45 Fig. 2 is a cross-sectional plan view of the cabinet along the lines 2—2 of Fig. 1;

50 Fig. 3 is a fragmentary cross-sectional view along the lines 3—3 of Fig. 1;

55 Fig. 4 is a cross-sectional view through the cathode ray tube;

Fig. 5 is a cross-sectional view through the loud speaker;

Fig. 6 is an exploded view illustrating the man-

ner in which the front plate is supported in the cabinet; and

Figs. 7 and 8 are detailed views illustrating a modified mounting for the bottom rail of the cabinet.

In practicing the invention there is provided a cabinet for a television receiver which is of rectangular configuration and of minimum size to contain a cathode ray tube with the screen of the cathode ray tube and a loud speaker positioned adjacent the front wall of the cabinet. A one-piece plastic front plate is provided which covers substantially the entire front wall of the cabinet and contains a window in front of the screen of the cathode ray tubes and apertures in front of the loud speaker. A resilient gasket is supported on the front wall of the cabinet in engagement with the front plate and forms a resilient mounting for the front end of the cathode ray tube. The neck of the cathode ray tube is supported from the top of the cabinet so that the tube is supported entirely by the cabinet. A chassis is provided for the television receiver which rests on the bottom wall of the cabinet and is removable therefrom independently of the cathode ray tube and the loud speaker.

In Figs. 1 and 2 there is illustrated a television receiver in accordance with the invention including cabinet 10 having a front wall 11, top wall 12, bottom wall 13 and side walls 14. The front wall 11 includes a top rail 15 and a removable bottom rail 16 which support therebetween a front plate 17 as will hereinafter be described. The front plate 17 may be of one-piece plastic construction including a transparent window portion 18 and apertures 19. As is apparent from the drawings, the window 18 is positioned in front of the face of the cathode ray tube 20, and the apertures 19 are positioned in front of the loud speaker 21. The cathode ray tube 20 is supported at the front end in a resilient gasket 22 supported in the front wall 11, and the neck thereof is supported by a bracket 23 which is mounted on the top wall 12 of the cabinet. The loud speaker 21 is also supported on the front wall 11 of the cabinet and includes a diaphragm 24 (Fig. 2) which is positioned adjacent an aperture 25 in the front wall. A suitable grille cloth 26 is positioned on support 27 to be immediately back of the openings 19 in the front plate 17.

As previously stated, the front end of the cathode ray tube is supported by resilient gasket 22 which is mounted on the front wall 11 of the cabinet. As best illustrated in Figs. 2, 3 and 4, the gasket has a tube supporting surface 30 of the same general configuration as the front end of the tube. The gasket also includes an outer annular groove 31 adapted to fit over the edge of an annular opening 32 in the front wall to hold the gasket on the front wall. The resilient mounting for the tube permits the receiver to be shipped with the tube in place. This is a distinct advantage as separate shipment of the tube requires packing thereof and installation of the tube after shipment of the receiver. The gasket 22 fits tightly against the front plate 17 and includes an opening 29 slightly larger than the window 18 but of generally the same shape. The front plate 17 includes a ribbed section 33 around the window 18 which cooperates with the resilient gasket to provide a tight seal between the gasket 22 and the front plate 17. This is for the purpose of preventing foreign material from entering the space between the front of the tube and the window which would produce an unattractive

appearance and would partially obstruct the view of the cathode ray tube. The gasket 22 may be made of a resilient material such as sponge rubber and should be of a relatively light color so that a shadow is not caused on the face of the tube adjacent the gasket. The gasket should preferably be of a color substantially the same as that of the face of the cathode ray tube. As previously stated, the tube 20 is supported at the neck portion thereof by bracket 23 mounted on the top wall 12 of the cabinet. As illustrated in Figs. 1, 2 and 4, the bracket includes a block 35 having a bottom surface 36 thereof curved to conform to the shape of the tube. A U-shaped strap 37, supported adjacent the top of the cabinet by bolts 38, holds the tube against the block 35 so that the neck portion of the tube is firmly supported to the top wall of the cabinet.

A chassis 40 is provided on the bottom wall 13 of the cabinet and is supported completely independently of the mounting of the cathode ray tube and the loud speaker so that the chassis can be removed from the cabinet without changing the position of either the cathode ray tube or the loud speaker. Control knobs 41 are removably positioned on shafts 42 which project from the chassis 40. The knobs 41 may be easily removable so that the shafts 42 can be withdrawn when it is desired to remove the chassis 40 from the cabinet 10. The chassis 40 includes electrical components such as vacuum tubes 43, coils 44, and power supply 45 which may be connected in any suitable television receiver circuit. The chassis is of L-shape having a cut-out portion 49 under the large portion of the tube 20. A removable plate 47 may be placed between the chassis 40 and the bottom wall 13 of the cabinet, and the bottom wall may have an opening 48 therein as best shown in Fig. 4 to permit servicing of the chassis without removing the chassis from the cabinet. In order to provide ventilation of the components of the receiver on the chassis, openings 46 are provided in the bottom wall 13 to allow circulation of air about the chassis (Fig. 2). Openings are also provided in the side walls of the cabinet adjacent the top thereof as illustrated in Fig. 6. These openings have been found to provide sufficient ventilation to remove the heat produced by a television receiver and thereby prevent over-heating of the various components of the receiver.

Referring now more particularly to the front plate 17, this plate may be constructed of transparent material which can be formed into the desired configuration. A transparent plastic material such as methyl methacrylate has been found to be particularly satisfactory, but it is to be noted that any other material which is completely clear to form a highly transparent window 18 may be used. The material used should not be so soft that it scratches easily so that the front plate and particularly the window would be easily defaced. As is apparent from Figs. 3 and 4, the portion of the front plate in front of the tube 20 is curved, and in addition to providing a window for viewing the tube, also serves as a protector for the front of the tube. For this reason a very strong plastic material is preferable so that the protective qualities will be great. The curve in the plate also increases the strength of the plate. Tests have indicated that plates made from methyl methacrylate will absorb very heavy direct blows. Further, if the plate does crack, splinters will not be produced as with safety glass or other transparent materials. Methyl meth-

acrylate is also a very clear material so that the brilliance of the tube is not materially reduced thereby. The window 18 may also be formed as a lens so that the picture which is produced on the curved screen on the face of the cathode ray tube 20 appears as a flat image. Further, the lens formed in front of the screen may be effective to enlarge the image produced on the screen of the tube so that it is easier to view the image. As previously stated, the front plate 17 also operates with the resilient gasket 22 to seal the space between the window and the face of the cathode ray tube against the entry of foreign particles. This eliminates the need for making the window removable so that the face of the tube as well as the window can be cleaned. The portion of the front plate extending in front of the loud speaker includes apertures as previously described and the apertures may be in the form of louvers as illustrated to provide a pleasing appearance. The portions of the front plate other than the window 18 should preferably be opaque and this can be accomplished by painting the back side of the plate over the entire surface thereof with the exception of the window 18. The use of a gold lacquer spray has been used and provides a very pleasing appearance.

In Fig. 6 there is illustrated the manner in which the front plate 17 is secured to the cabinet 10. As previously stated, the plate is supported between the top rail 15 and the movable bottom rail 16. It is to be noted from Fig. 6 that the front plate 17 includes ribs 50 on the top and bottom edges thereof. These ribs are adapted to fit in grooves 51 and 52 in the rails 15 and 16, respectively. The front plate 17 is slightly bowed when it is formed and spaced along the ribs 50 thereof are wedge-shaped projections 53. It will, therefore, be seen that when the rib 50 is placed in the groove 51 in the rail 15, the straightening of the plate to fit in the groove will cause the plate to remain in a predetermined position. The projection 53 will wedge into the edge of the groove to further hold the plate 17 in position. The bowing of the plate will cause the ends 54 thereof to bear firmly against the sides 14 of the cabinet to thereby provide a very neat appearance. After the front plate 17 is in place the movable rail 16 can then be positioned in place with the groove 52 therein engaging the bottom projection 50 of the front plate. The wedge-shaped projections will hold the front plate securely in position with respect to the rail as described with regard to the engagement of the plate 17 at the top with rail 15. The movable rail 16 may then be secured to the cabinet as by screws 55 which extend through the front wall 11 of the cabinet into the rail 16.

In Figs. 7 and 8 there is illustrated a modified construction for securing the movable bottom rail 16 to the cabinet. In this construction an L-shaped bracket 60 is secured to the movable rail 16 by screws 61. This bracket extends on the inside of the side walls 14 of the cabinet and has a threaded opening 62 aligned with an opening 63 in the side wall. A screw 64 is provided in a recess 65 in the side wall 14 and threadably engages the opening 62 in bracket 60 to thereby hold the rail 16 in position on the cabinet. Brackets as disclosed will be provided on either end of the rail 16 to engage the two side walls of the cabinet. The recesses 65 may be covered as by buttons 66 to provide a more attractive appearance.

The portion of the front plate 17 in front of the tube 20 is curved to conform generally with the contour of the tube. This allows the tube to project through the front wall 11 of the cabinet 5 and to be positioned very close to the extreme front surface of the cabinet. As presently available cathode ray tubes are relatively long and as it is desired to provide the receivers in relatively small cabinets, it will be apparent that 10 this construction permits the use of cabinets of minimum depth. The height of the cabinet in the structure shown is also limited by the size of the cathode ray tube, the cabinet being of only slightly greater height than the diameter of the cathode ray tube. This is accomplished by providing the cut-out 49 in the chassis 40. The width of the cabinet is limited by the sum of the diameters of the cathode ray tube 20 and the loud speaker 21 and is not substantially 15 greater than this sum. In order to provide a realistic effect in television receivers, it is essential that the sound be directed from a point closely adjacent to the screen and be directed toward the persons who are viewing the screen. 20 To fulfill these conditions, the speaker must be mounted on the front wall of the cabinet along with the screen of the tube and, therefore, it is essential that the front wall of the receiver be 25 of sufficient size to accommodate both the front 30 of the picture tube and the loud speaker which reproduces the sound. In a cabinet actually constructed for housing a receiver including a cathode ray tube with a screen seven inches in diameter, the over-all height of the cabinet was 35 approximately 9 1/4 inches, the width was approximately 16 3/4 inches, and the over-all depth was approximately 16 1/4 inches.

It is, therefore, seen that there is provided a 40 television receiver in which the components are arranged so that they may be housed in a cabinet of minimum size. The cabinet is of simple rectangular configuration having a one-piece front plate which covers substantially the entire front 45 of the cabinet. The front plate forms a window for the screen of the cathode ray tube of the receiver and serves as a protector for the tube and also improves the picture appearing thereon. The resilient gasket for supporting the front end 50 of the tube provides a satisfactory support for the tube even during shipment so that the receiver can be shipped with the tube in place thereby eliminating special packing for the tube and the installation of the tube in the cabinet 55 after shipment. The resilient gasket also prevents entry of dust in the space between the protector and the front of the tube to eliminate the need of cleaning the surfaces.

Although there have been disclosed certain 60 embodiments of our invention, it is obvious that various changes and modifications can be made therein without departing from the intended scope of the invention as defined in the appended claims.

We claim:

1. In a television receiver, a cabinet, a plate extending across the front of said cabinet of said receiver including a transparent section and an opaque ribbed border about said transparent section, a cathode ray tube supported in said cabinet and having the face thereof positioned adjacent said transparent section, a resilient gasket supported on said cabinet and positioned between said face of said tube and said plate, said gasket forming a resilient mounting for sealing

the space between said face of said tube and said plate to prevent entry of foreign material therebetween, said gasket being of substantially the same color as said face of said tube and forming with said opaque border a mask about said face of said tube.

2. In a television receiver having a cabinet with an opening across the front thereof and having within the cabinet sound-producing means and a cathode ray tube with a curved front face, the combination including a one-piece plate of molded plastic material mounted at the opening across the cabinet front and including a closed transparent portion in front of said tube-front-face and an apertured portion in front of said sound producing means, said transparent portion being curved to conform to the contour of the tube-front-face, and resilient gasket means intermediate the plate and said tube at the curved front face, said gasket being of such a size to form a border at said front face and forming a resilient mounting for the front of the tube.

3. In the television receiver as defined in claim 2 said closed transparent portion being of such a configuration as to form a lens for enlarging and flattening the picture indication visible at said tube-front-face.

4. In electronic apparatus including means with a screen for producing visual indications and including means for producing sound, the combination comprising a cabinet for enclosing said apparatus including at the front thereof a front plate mounted in the cabinet and having a transparent portion positioned in front of said screen and a perforated portion in front of said sound producing means, resilient gasket means at the periphery of said screen and maintained between said periphery and said front plate, said plate being slightly curved longitudinally of said cabinet front and including a rib along at least one longitudinal edge thereof, and a rail removably mounted on said cabinet at the front having a straight depression therein engaging said rib of said plate to straighten said rib and the plate to tension the same and hold the plate securely in the cabinet.

5. In a television receiver, a cabinet having a front wall with a transparent section therein, a cathode ray tube supported in said cabinet and having the face thereof positioned adjacent said transparent section, a resilient gasket supported by said cabinet entirely inside said front wall engaging said face and providing a resilient mounting for said face of said tube, said gasket having a front thin edge abutting said front wall of said cabinet and positioned between said face of said tube and said wall so that said tube face extends closely adjacent said wall, said gasket having an enlarged portion at the back thereof with a groove therein, and means engaging said groove for supporting said gasket inside said cabinet.

6. A television receiver having a cabinet with walls at the top, bottom and front thereof, said front wall including a closed transparent portion, a cathode ray tube in said cabinet, supporting means secured to said top wall, resilient means engaging the inside of the front wall of said cabinet adjacent said closed transparent portion, said cathode ray tube having the front face thereof positioned at said closed transparent portion and engaging said resilient means, said supporting means and said resilient means combining to

support said cathode ray tube in said cabinet, and a chassis including circuit components of said television receiver, said chassis being supported on said bottom wall of said cabinet and removable therefrom independently of the cathode ray tube.

7. A television receiver comprising a cathode ray tube having an enlarged front portion, a loudspeaker with a front face portion, a rectangular walled cabinet the inside vertical dimension of which is substantially the same as the vertical dimension of said enlarged front portion and the inside horizontal dimension of which is approximately equal to the sum of the horizontal dimension across said enlarged portion and the horizontal dimension across the face of said loudspeaker, said cabinet having a front wall with a closed transparent portion on one side and an apertured portion on the other side, a receiver chassis supported on the bottom wall of said cabinet and covering substantially the entire area of said bottom wall, said chassis having a cut-out portion therein on the side adjacent said transparent portion of said front wall, said chassis including a section on the side opposite to said cut-out portion adjacent said front wall, components on said chassis section having controls extending through openings in said front wall of said cabinet to be operated at the front of said cabinet, said loudspeaker being positioned above said chassis section at said apertured portion, and said cathode ray tube being positioned in said cabinet with said enlarged front portion at said closed transparent portion of said front wall and extending into said cut-out portion of said chassis.

8. A television receiver employing a cathode ray tube and comprising a walled cabinet corresponding in vertical dimension substantially to the largest vertical dimension of a cathode ray tube therein, said cabinet having a front wall with a closed transparent portion and a portion with openings therein, a chassis supported on the bottom wall of said cabinet, said chassis having a cut-out portion on one side thereof adjacent said front wall, adjustable circuit components mounted on the side of said chassis opposite to said one side adjacent said front wall, said adjustable components having operating controls extending through said openings in said cabinet front wall for operation from the front of said cabinet, and a cathode ray tube in said cabinet having an enlarged portion and a screen therein positioned adjacent said closed transparent portion of said cabinet front wall, said cathode ray tube enlarged portion extending in the space provided by said cut-out portion of said chassis and corresponding in its largest vertical dimension substantially to the inside vertical dimension of the cabinet.

9. A television receiver comprising a cathode ray tube having an enlarged front portion, a walled cabinet the inside vertical dimension of which is substantially the same as the diameter of said enlarged portion of said tube, said cabinet having a front wall with a closed transparent portion and a portion with openings therein, a resilient mask engaging said front wall and positioned about said transparent portion, a receiver chassis supported on the bottom wall of said cabinet, said chassis having a cut-out portion therein on the side adjacent said transparent portion of said cabinet front wall, and circuit components mounted on said chassis on the other side thereof adjacent said front wall of said cabinet, said components having controls extend-

ing through said openings in said front of said cabinet, said cathode ray tube being positioned in said cabinet with the enlarged end portion thereof extending into said cut-out portion of said chassis and engaging said mask.
